UNITED STATES PATENT OFFICE.

HUGH L. THOMPSON, OF WATERBURY, CONNECTICUT.

ANNEALING-FURNACE.

No. 890,314.

Specification of Letters Patent.

Patented June 9, 1908.

Application filed May 27, 1905, Serial No. 262,544. Renewed November 7, 1907. Serial No. 401,164.

To all whom it may concern:

Be it known that I, HUGH L. THOMPSON, a citizen of the United States, residing at Waterbury, in the county of New Haven and 5 State of Connecticut, have invented a new and useful Annealing-Furnace, of which the following is a specification.

My invention relates to annealing furnaces in which the oxidizing atmosphere is 10 excluded from the metal during treatment and until the same has been cooled.

My object is to provide improved means for delivering the metal to the furnace retort without admitting the oxidizing atmosphere 15 thereto.

My invention comprises an annealing retort and a mechanical air lock through which the material is carried into the retort.

My improved means is especially adapted 20 for the treatment of metal in the form of sheets, but may obviously be used for metal in other forms by the proper shaping of the valves or gates.

My improved annealing furnace is especially adapted for continuous operation and includes a preliminary chamber through 25 which the metal must pass before reaching the retort chamber. This preliminary chamber is mechanically sealed from the outside atmosphere and is also mechanically sealed 30 from the retort and means are provided for exhausting the oxidizing atmosphere from this preliminary chamber throughout the operation of the device.

My invention also comprises a similar 35 chamber at the discharge end of the retort which is also provided with means for exhausting the oxidizing atmosphere therefrom. I also provide means in this chamber 40 for the cooling of the metal as it passes therethrough so that as the metal is delivered to the outside atmosphere it has been so reduced in temperature as not to be oxidized thereby.

Referring to the drawings:—Figure 1 is a 45 longitudinal vertical section of an annealing furnace showing my improved mechanism. Fig. 2 is a similar view enlarged of the preliminary charging chamber. Fig. 3 is a 50 cross section on line 3', 3' of Fig. 2. Fig. 4 is a cross section on line 4', 4' of Fig. 3.

Similar numerals refer to similar parts throughout the several views.

Referring to Fig. 1, 1 represents the retort 5 of the usual form through which the metal 2 is carried from reel 3 to reel 4. Before the

metal 2 reaches the retort 1 however it is passed through the preliminary charging chamber 5 which is maintained automatically closed against the outside atmosphere by 60 the flexible gates 6 and 7. These gates are composed of asbestos, felt or other flexible or yielding material and are preferably stiffened by the framework 8 and 9 which are secured by hinges 10 and 11 operating on rods 37 65 and 38 secured to the stationary structure. The flexible gate 6 is maintained closed against the metal by gravity while the flexible gate 7 is maintained closed by the counterbalance 12. This preliminary charging 70 chamber is also sealed against the retort by the flexible gates 13 and 14 supported and operating in substantially the same manner as 6 and 7. Steam, gas or other non-oxidizing agent is introduced through pipe 15 to 75 force the oxidizing atmosphere out of chamber 5 through pipe 16 so that the metal traveling through the gates 13 and 14 carries practically no oxidizing atmosphere into the retort 1. The retort 1 is kept free of 80 oxidizing atmosphere in the usual way by the introduction of a non-oxidizing agent through pipe 17 to expel the oxidizing atmosphere through pipe 18. At the discharge end of retort 1 is provided a supplemental chamber 19, sealed from the retort by the flexible gates 20 and 21, the construction and operation of which are substantially the same as that described in connection with gates 6 and 7. This chamber 85 19 is also sealed from the outside atmosphere by the flexible gates 22 and 23 having similar construction and operation. Within the chamber 19 is provided a coil or nest of cooling pipes 39 which are adapted to surround 90 the metal 2 as the same passes through the chamber. The purpose of this cooling device is to reduce the temperature of the metal so that it will not be subject to the oxidizing effect of the outside atmosphere 100 when discharged from said chamber 19. This chamber 19 is similarly exhausted from oxidizing atmosphere by the introduction of a non-oxidizing agent through pipe 24 and the escape of the atmosphere through 105 pipe 25. For the purpose of introducing the first piece of metal through the retort and chambers I provide in chamber 5 the platform 26 and roller 27 for supporting and guiding the metal through gates 13 and 14. 110 The metal may then be pushed along the bottom of retort until it comes to the incline

28 when it is carried upwardly over roller 29 through gates 21 and 22.

Suitable rollers such as 30 will serve to direct the metal through gates 22 and 23. 5 When the metal is once threaded through the device one sheet is made to pull another through after it, that is, a supplemental reel such as 31 is usually provided and as reel 3 has become nearly empty the end of 10 metal 2 is secured by any of the well known devices provided for this purpose to the metal 2' on reel 31. When reel 4 is full the metal on the reel is separated from the metal coming through the retort by any suitable 15 well known device and the supplemental reel such as 32 is connected with the metal coming from the retort and so on. Suitable means are provided for rotating the reel so as to draw the metal through the retort 20 and wind the same on said reels. These are well known devices and are not described by me as they form no part of my invention.

If at any time it is desired to interrupt the annealing process a dummy band of 25 metal may be carried through the retort so as to project from either end thereof so that when it is desired to start the annealing process again the metal may be attached to this dummy at one end while the other end 30 of the dummy is secured to the rotating reel to draw metal through as above described. It will thus be evident that by shifting from an empty reel to a full reel at the charging end of the retort and from a full reel to an 35 empty reel at the discharging end of the retort from time to time as the same becomes necessary the annealing operation may be made continuous.

The roller 33 is especially adapted to maintain the position of the metal as it enters the 40 first pair of gates 6 and 7 so that it will always be maintained properly centered between said gates. The roller 27 serves a similar purpose with respect to gates 13 and 45 14, roller 29 with respect to gates 20 and 21, while the overhanging roller 44 serves the same purpose with respect to gates 22 and 23; the position of reel 4 being such as to always maintain the metal 2 either at the 50 same elevation or slightly above the elevation of the lowest point of roller 44.

Fig. 3 is a cross section of the retort showing an elevation of gates 13 and 14 in the 55 operative position, part of these gates being broken away to show the interior construction. Fig. 4 is a fragmentary view of the wall of the retort showing a shouldered or projecting portion 34 having the curved surfaces 35 and 36 as seats for the sides of the 60 flexible gates so that a tight joint is secured between the gates and the side walls of the retort and chamber.

As above stated, the gates are composed of a flexible material such as asbestos or felt 65 suitably treated to resist the heat. These

gates are pressed firmly together so that they will lie close to the metal 2 as the same passes between them. Fig. 3 shows these gates closed together at either side of the metal 2 so as to form a substantially air tight 70 seal around the metal.

While I have shown the chambers 5 and 19 combined with retort 1, it is obvious that either chamber may be used without the other by employing some other form of seal 75 such as the ordinary water seal at one end of the retort.

My device is especially useful in the annealing of metals which it is not desirable to pass through a liquid before entering the retort. This device is also useful as affording a cooling means for the metal in which the water or cooling liquid shall not come in contact with the metal. This is important in the treatment of certain kinds of metals. 80 85

What I claim is—

1. In an annealing furnace, the combination of a retort, a charging chamber delivering thereto, and a gate of yielding material for maintaining the chamber closed from the 90 retort while the metal to be treated passes therethrough.

2. In an annealing furnace, the combination of a retort, a charging chamber delivering thereto, and flexible gates for closing 95 the chamber from the retort at one end, and at the other end from the outside atmosphere, while the metal passes therethrough.

3. In an annealing furnace, the combination of a retort, a charging chamber delivering thereto, flexible gates for closing the chamber from the retort at one end, and at the other end from the outside atmosphere, while the metal passes therethrough, and means for displacing the oxidizing atmosphere in the charging chamber by a non-oxidizing agent. 100 105

4. In an annealing furnace, the combination of a retort, a charging chamber delivering thereto, and coöperating gates provided with yielding material at their contact edges to close about the metal passing therebetween, for maintaining a continuous seal between the charging chamber and the retort. 110 115

5. In an annealing furnace, the combination of a retort, a charging chamber delivering thereto, coöperating gates for closing the charging chamber from the retort at one end, and from the outside atmosphere at the 120 other end, said gates provided at their contacting edges with a yielding material for closing around the metal passing therebetween to maintain a continuous seal, and means for displacing the oxidizing atmosphere in the charging chamber by a non-oxidizing agent. 125

6. In an annealing furnace, the combination of a retort and an air lock therefor, formed by coöperating gates of flexible ma- 130

terial provided with counterbalanced means for maintaining pressure therebetween.

7. In an annealing furnace, the combination of a retort, a gate therefor, of flexible material, and a projection from the wall of the retort forming a seat for the gate to maintain a seal therewith.

8. In an annealing furnace, the combination of a retort and an air lock formed by 10 coöperating hinge supported gates of flexible or yielding material, through which the metal to be treated may pass.

9. In an annealing furnace, the combination of a retort, a chamber at the discharge 15 end of the retort, coöperating gates of flexible or yielding material closing said cham-

ber from the retort, means for displacing the oxidizing atmosphere in said chamber by a non-oxidizing agent, and means for cooling the metal passing therethrough.

10. In an annealing furnace, the combination of a retort, a chamber at the discharge end of the retort, coöperating gates of yielding material between the said chamber and retort, means for displacing the oxidizing 25 atmosphere in said chamber by a non-oxidizing agent, and cooling means within said chamber.

HUGH L. THOMPSON.
